UNITED STATES PATENT OFFICE.

CHARLES S. BURNETT, OF HOLYOKE, MASSACHUSETTS.

BOBBIN-STRIPPING MACHINE.

1,260,867.

Specification of Letters Patent. Patented Mar. 26, 1918.

Application filed October 1, 1913. Serial No. 792,715.

To all whom it may concern:

Be it known that I, CHARLES S. BURNETT, a citizen of the United States, residing at Holyoke, county of Hampden, State of Massachusetts, have invented an Improvement 5 in Bobbin-Stripping Machines, of which the following description, in connection with the accompanying drawing, is a specification, like characters on the drawing representing like parts.

This invention relates to improvements in bobbin strippers for removing the waste from bobbins used in automatic replenishing looms.

15 One of the objects of the present invention is to simplify the construction of bobbin stripping machines, and to provide mechanism which will cleanly remove the waste from the barrel of the bobbin at a rapid rate.

20 Another object of the invention is to provide a bobbin stripper which can be easily supplied with bobbins by an unskilled workman, and which will not be likely to cause injury if the hand of the workman should 25 become engaged in the stripping jaws.

Another object of the invention is to provide a double acting machine in which a plurality of operators may be employed in 30 feeding bobbins to the stripping devices, and whereby the bobbins will be alternately stripped, thereby increasing the efficiency of the machine, economizing floor space, and saving power.

35 In the present invention these objects are attained by the provision of a stationary pair of stripping jaws, which are yieldingly pressed together with such comparatively light pressure that the engagement of the 40 operator's finger in said jaws will not cause serious injury, and by the provision of a reciprocating gripper adapted to engage the base of the bobbin and draw the barrel thereof through the stripping jaws, thereby 45 removing the waste which remains upon said barrel. A more complete disclosure of the objects and nature of this invention will appear from the following description and drawing, and the annexed claims.

50 In the drawings:—
Figure 1 represents the side view of the

machine partially broken away to show the driving mechanism.

Fig. 2 is a plan view of the machine showing, in dotted lines, mechanism for opening 55 and closing the stripping jaws.

Fig. 3 is an enlarged plan view of the stripping jaws and the grippers, showing the same in engagement with the bobbin, a portion of the jaws and of the gripping 60 mechanism being broken away to more fully illustrate its construction.

Fig. 4 is a vertical sectional view in a plane adjacent to the faces of the stripping jaws, and

65 Fig. 5 is a side elevation of the bobbin lying upon the bobbin supports showing a portion of one of the stripping jaws, and the portion of the guide for the bobbin base in section.

70 In a preferred embodiment of the invention illustrated in the drawing a table is provided comprising a top 1 supported by suitable legs 2, and having cross-bars 3 securing the lower ends of the legs together 75 in the ordinary manner, and vertical posts or legs 4 adapted to support the driving mechanism, hereafter to be described.

75 The stripping mechanism, which comprises two sets of oppositely disposed stripping jaws and a reciprocating cross-head carrying gripping mechanism at each end, is supported upon the top 1 of the table, the actuating mechanism therefor being located beneath said table top, so that it is 80 concealed from the reach of the operator. The stripping mechanism comprises a pair of jaws 5, 6, which are preferably provided with concave removable and adjustable faces 7 constructed of fibrous material, preferably 85 wood, softer than that of which the bobbin is made in order to avoid injury to the bobbin by the contact of the stripping jaws therewith. By constructing the jaws of fibrous material such as wood the granular 90 ends of the fibers engage more effectively the fibers of the waste which remains upon the bobbin and this fibrous engaging surface remains notwithstanding the wearing down of the bobbin engaging face presenting a 95 somewhat roughened surface, instead of a smooth polished surface such as would be 100

presented by worn metallic faces. The stripping jaws are pivotally mounted upon the bolts 8 extending through upwardly projecting lugs or bosses 9 secured to the table 5 1 by screws or bolts, or in any other suitable manner. The jaws 5, 6, are provided respectively with downwardly extended arms 10, 11, which serve as levers to actuate the jaws. The lower ends of said levers 10, 11 10 are connected by springs 12, 12, to the frame by suitable adjustable bolts 13, by which the tension upon said springs may be adjusted as desired. The springs 12 serve normally to keep the jaws 5, 6 closed. 15 In order to provide for the ready insertion of the bobbin, means are provided for causing the ends of the levers 10, 11 to approach each other, and thereby separate the jaws. This mechanism, in the form illustrated in the drawing, comprises a bell crank lever 14 pivoted at its elbow upon a bolt 15 which enters the bottom of the table top 1. One end of the lever 14 is adapted to engage the outer edge of the lever 10, and 20 upon actuation press the same inwardly. Attached to this end of the lever is a link 16 which is pivotally connected at its other end to a lever 17, which is likewise pivoted near its middle upon a bolt 18 extending into 25 the table top 1. The other end of the lever 17 engages the outer edge of the downwardly extending lever 11 of the jaw 6. Motion is given to the bell crank lever through a link 19 which engages a cam 20 upon a counter- 30 shaft 21, which is driven in turn through suitable gearing from the main shaft 22 which is journaled in the bearings carried by the upright 4, and has a loose pulley 23 and a tight pulley 24 provided with suitable belt 35 40 shifting mechanism 25.

In the embodiment of the invention shown in the drawing the end of the link 19 is connected to a link 26, one end of which is pivoted at 27 to the frame of the machine, the 45 cam 20 engages the side of the links 26, and thereby operates the bell crank lever. These parts may be made in duplicate and oppositely disposed at the ends of the table 1. It will be obvious from the above description 50 read in connection with the drawings that when the cam 20 engages a link 26 and forces the same toward the end of the table it will cause the bell crank lever to rock upon its pivot 15, thereby pressing its other end 55 against the lower lever 10 of the jaw, and at the same time, through the connection 16, operate the lever 17 to press its end against the lever 11 of the jaw 6, thereby causing the levers 10 and 11 to approach each other 60 and consequently opening the stripping jaws for the reception of the bobbin.

The gripping mechanism comprises a reciprocating cross-head 28 which, as illustrated in the drawing, is substantially square

in cross section, and is supported in standards 29 suitably secured to the top 1 of the table. The standards 29 are each provided with anti-friction rolls 30, 31 located relatively beneath and above the cross-heads. These standards 29 are also provided with 70 guides 32 which are adapted to coöperate with the grippers, hereinafter to be described.

The cross head is provided at each end with mechanism adapted to engage the base 75 of a bobbin supported in the stripping jaws. In the preferred form of the invention illustrated in the drawings herein, the ends of the cross head are recessed to receive the fulcrums of the levers 33. The forward ends 80 of the levers 33 are provided with serrated jaws 34, said jaws being rounded at their ends in such a manner as to slide easily over the base of the bobbin, when thrust against the same, the serrations in said jaws being 85 adapted to engage the rings upon the bobbin base. The rearward ends 35 of said levers 33 are curved, and are adapted upon retraction to enter between and engage the guides 32, for the purpose of opening the 90 jaws to discharge the stripped bobbin. The jaws of the gripper are normally held in a relatively close position by springs 36, which are seated in recesses 37 in the cross head 28, and abut against the inner edges of said 95 levers 33.

Any suitable mechanism may be used for reciprocating the cross head 28. In the embodiment of the invention shown in the drawing, this mechanism consists of a substantially vertical lever 38 pivoted at its bottom upon a cross shaft 39 mounted upon the cross pieces 3 of the frame, and connected at its upper end by a pin and slot connection 40 to the cross head 28. This lever is 105 rocked about its pivotal support 29 through a crank 41 upon the shaft 21 which drives a pitman 42 which is pivotally connected to an adjustable sleeve 43, embracing the lever 38 somewhat above the middle. The sleeve 43 110 is provided with a set screw 44, which is adapted to secure the same in any desired position. It will be observed that by adjusting the sleeve 43 along the lever 38 toward or from its pivot 39, the amplitude of vibration of the cross head 40 may be accurately determined. This feature of adjustment is important for the reason that it is desirable to have the gripping jaws carried just far enough to engage the rings on the base of 115 the bobbin, as further movement would not only be useless, but would cause the likelihood of the faces of the jaws scratching the bobbin base. Furthermore, any substantial movement of the jaws beyond their proper 120 positions would result in contacting with the stripping jaws, and would be likely to damage the same.

The bobbin may be properly supported in its place between the gripping jaws by suitable guides. As illustrated in the drawing, the barrel of the bobbin is supported upon a 5 guide 45, which is constructed of wood, and the base of the bobbin is supported by a guide 46, which, as illustrated, comprises an angular metallic support which is secured to the table top 1 in any suitable manner, and 10 extends upwardly therefrom to the proper height to aline the bobbin with the concave portion of the stripping jaws, and is then bent at right angles to give a broad support for the bobbin base.

15 In order to insure the proper positioning of the bobbins upon the supports and between the stripping jaws, a guide may be provided for directing the base of the bobbin into proper position. As illustrated in 20 the drawing, this guide comprises a vertical plate 47 concaved at its inner portion 48 to provide a channel which will direct the bobbin medially of the stripping jaws, and to position it so that the grippers may properly 25 engage the rings upon the bobbin base. The lower portion of the guide is cut away at 49 to provide a passage for the gripping jaws when the same advance to engage the base of the bobbin, as is illustrated in Fig. 5.

30 In operating the device the operator grasps the bobbin by the barrel or spindle, and places the same between the stripping jaws so that the jaws are adjacent to the base of the bobbin. This positioning of the 35 bobbin occurs, of course, during the period that the jaws are open. The gripper then advances and the jaws are closed simultaneously therewith. When the gripper has reached nearly the extent of its forward 40 movement, the forward ends of the levers 33 ride up over the base of the bobbin, which is, at that time, held from longitudinal movement by the stripping jaws, and the serrations 34 engage over the rings of the bobbin

45 base. Upon the reverse movement of the cross head the bobbin is drawn through the stripping jaws, and the waste filling upon the bobbin is stripped off over the nose of the bobbin. Upon nearing the limit of the 50 backward movement of the cross head, the arms 35 of the levers 33 engage the guides 32, which cause the arms 35 to approach each other, thereby opening the jaws of the gripper and releasing the bobbin which drops 55 into a suitable bobbin chute 50, or other suitable receptacle.

In the preferred form of the invention the reciprocating cross head is provided at each end with gripping jaws, and suitable stripping members are provided to coöperate therewith, as above set forth. It will be obvious that a plurality of cross heads may be joined together, if found necessary or desirable, and that such duplication may be con-

tinued until as many strippers as are desirable are provided.

By reason of the simple construction of the bobbin stripper above described, there is little liability to breakage which will put the device out of commission and thereby limit 70 the supply of bobbins for refilling. This is, of course, very important, since a failure of the bobbin stripper to operate would be likely to cause an accumulation of bobbins bearing waste, and if the supply of stripped 75 bobbins should become exhausted, would delay the operation of the looms.

The device above described is also of such a character that bobbins may be placed therein by an unskilled operator, since it involves merely the placing of the bobbin between the stripping jaws. If the bobbin is placed improperly between the jaws no harm is done, for the reason that the jaws will either thrust it out of the way, or if they 80 succeed in gripping, will properly strip the same. Furthermore, the stripping jaws being yieldably mounted, and the springs 12 of light tension, the operator will not become injured if the fingers should accidentally 85 become engaged by the stripping jaws. The gripping jaws are normally held a sufficient distance apart by a separator 51 to go over the bobbin base, and there is therefore no 90 danger of the operator's hand becoming 95 caught in this large opening. Even if it should occur, the gripping jaws are likewise yieldably mounted and are positively released at the end of the stroke. This construction renders it almost impossible for an 100 operator to be injured in any way, especially as the driving mechanism is wholly concealed beneath the table. The stripping performed by this device is found in practice to be exceedingly efficient and the speed of 105 the operation of the device is, of course, limited only by the capacity of the operators to feed bobbins into the same.

By reason of the fact that the stripping jaws remain stationary while the gripping 110 mechanism reciprocates, and stand above the surface of the table, there is no likelihood of the waste becoming soiled by oil or dirt. In the operation of the stripping machine the waste from the stripped bobbin falls 115 from the table in front of the operator and can be readily pushed therefrom into a suitable receptacle.

Having fully described my invention, what I claim as new, and desire to secure by 120 Letters Patent is:

1. In a bobbin stripping machine comprising a pair of yieldable stripping jaws, a reciprocating cross-head, a pair of yieldable gripping jaws pivoted at the end thereof and having rearwardly extending shanks, means for reciprocating said cross-head, whereby the gripping jaws are caused to engage the

- base of a bobbin and draw the barrel thereof through said stripping jaws, and guides adapted to compress the shanks of said gripping jaws upon their retraction and thereby cause them to release the bobbin.
2. In a bobbin stripping machine, yieldable stripping jaws adapted to engage the barrel of a bobbin, means for separating said stripping jaws for the reception of the bobbin, a support for said bobbin, a guide for the base thereof, a reciprocating gripper adapted to engage the base of the bobbin and draw the barrel thereof through said stripping jaws, and means for releasing the stripped bobbin from said gripper.
3. A double acting stripper comprising a plurality of sets of stripping members and a reciprocating member having means adapted to alternately engage bobbins held by the respective stripping members and draw the barrels thereof through said stripping members.
4. A double acting bobbin stripper comprising two sets of stripping members, a reciprocating cross-head having grippers at its opposite ends adapted to engage bobbins held by said stripping members, and means for reciprocating said cross-head.
5. A double acting bobbin stripper comprising two sets of stripping jaws adapted to engage the barrels of bobbins, a reciprocating cross-head, a pair of grippers pivotally mounted upon each end of said cross-head and adapted to engage the bases of bobbins held by the respective stripping jaws and means for releasing the stripped bobbins from said grippers.
6. A bobbin stripper comprising stripping members, a gripper having spring jaws adapted to engage the base of the bobbin and draw the barrel thereof through said stripping means, a crank shaft connected to said gripper and means intermediate of said crank shaft and said gripper for adjusting the amplitude of movement of said gripper.
7. A bobbin stripper comprising stripping members, a reciprocating cross head having grippers adapted to engage the base of the bobbin and draw the barrel thereof through said stripping members, means for reciprocating said cross head comprising a lever pivotally connected to said cross head, a crank shaft and a pitman adjustably connected to said lever intermediate of its ends and journaled upon said crank shaft whereby the amplitude of movement of the reciprocating cross head and grippers may be adjusted.
8. A bobbin stripper comprising stripping members, a reciprocating cross-head having grippers at its opposite ends adapted to engage bobbins held by said stripping members, and means for reciprocating said cross-head comprising a lever pivotally connected thereto at one end and pivotally supported at its other end, and operating means engaging said lever intermediate of its ends.
9. A double acting bobbin stripper comprising two sets of stripping members, a reciprocating cross-head having grippers at its opposite ends adapted to engage bobbins held by said stripping members, means for reciprocating said cross-head comprising a lever and a pitman adjustably connected to said lever intermediate of its ends, whereby the amplitude of movement of said cross-head may be adjusted, and means for actuating said pitman.
10. A bobbin stripper comprising a pair of yieldably mounted concaved stripping jaws, a pair of slotted standards in alignment with the concaved openings in said jaws, antifriction rolls in said standards, a reciprocating cross head carried by said rolls having grippers at its end adapted to engage bobbins held by said stripping members, means for reciprocating said cross head and means carried by said standards adapted to open said stripping jaws to release the bobbin therefrom.
11. In a bobbin stripping machine comprising a pair of stripping jaws at each end of the machine and means consisting of positively operated gripping members co-operating with said stripping jaws to draw the barrel of the bobbin through said stripping jaws, removable faces of fibrous material for said jaws adapted to engage the bobbin barrel during the stripping operation whereby injury to the bobbin barrel will be prevented.
12. In a bobbin stripping machine comprising a pair of stripping jaws at each end of the machine and means consisting of positively operated gripping members co-operating with said stripping jaws to strip a bobbin, wooden faces for said jaws of softer material than the barrel of the bobbin which are engaged thereby during the stripping operation.
13. In a bobbin stripping machine, a slide and means for reciprocating the same, a pair of bobbin gripping jaws at each end of the slide, means for actuating these jaws to cause them to grip the head of the bobbin, means for actuating these jaws to cause them to release the bobbin as the slide approaches the center of the machine, and automatic means for stripping the waste yarn from the bobbin during the inward movement of each end of the slide.
14. A bobbin stripper comprising a table, stripping members having bobbin engaging means and a relatively movable co-operating gripper adapted to draw a bobbin through said stripping members to remove the waste

therefrom mounted on said table, or means for actuating said stripping members and said gripper located wholly beneath said table and concealed thereby, whereby the operator is protected from injury from said actuating means.

15. A double acting stripper comprising a plurality of sets of stripping members and a reciprocating member having means adapted alternately to engage bobbins held by

the respective stripping members and move the barrels thereof through said stripping members.

In testimony whereof, I have signed my name to this specification, in the presence of 15 two subscribing witnesses.
